UNITED STATES PATENT OFFICE.

ADOLPH NEUSCHOTZ, OF NEW YORK, N. Y.

DESIGN FOR A MEMORIAL MONUMENT.

No. 39,864.

Specification for Design.

Patented March 9, 1909.

Application filed September 21, 1908. Serial No. 454,127. Term of patent 14 years.

To all whom it may concern:

Be it known that I, ADOLPH NEUSCHOTZ, a citizen of the United States, residing in the borough of Manhattan, in the city and State of New York, have invented a new, original, and ornamental Design for a Memorial Monument, of which the following is a specification, reference being had to the accompanying drawing, forming a part thereof.

The figure is a perspective view of the memorial, showing my new design, and comprising a small monument of a size adapted to be placed on a suitable table, mantel or shelf in a living room, and having near the top thereof a medallion which may comprise a small portrait of a deceased person. Below the latter is a tablet which may contain

the person's name, together with suitable words commemorating his or her death. The base of the monument is provided with a dial or dials having thereon the names of the months and the numerals indicating the days of the month. The dials are adapted to have suitable pointers or hands attached to or painted thereon and radiating from the center of the dials to indicate the date upon which a person was born or died.

I claim—

The ornamental design for a memorial monument substantially as shown in the drawing and described in the specification.

ADOLPH NEUSCHOTZ.
